UNITED STATES PATENT OFFICE.

HENRY WILCOX, OF NEWARK, NEW JERSEY, ASSIGNOR TO FRANK BRABSON, OF NEWARK, NEW JERSEY.

CLOCK-OPERATED CONTROL DEVICE.

1,383,649.

Specification of Letters Patent. Patented Mar. 16, 1920.

Application filed August 21, 1916. Serial No. 115,954.

To all whom it may concern:

Be it known that I, HENRY WILCOX, a citizen of the United States of America, and a resident of Newark, in the county of Essex and State of New Jersey, have invented certain new and useful Improvements in Clock-Operated Control Devices, of which the following is a specification.

The objects of this invention are to provide an improved device adapted to be controlled by a clock for operating suitable mechanism to effect a desired result at a given time; to secure simplicity, ease of manipulation and freedom from wear and getting out of order; to enable the device to be readily set for any given time; to provide an adjustment whereby the clock may be caused to operate the drafts at substantially the time for which it is set; to minimize the strain on the clock works; to particularly adapt the device to opening the drafts of a furnace; to enable the device to be applied to furnaces in different ways, and thus adapted to various kinds of furnaces; to provide improved means for holding the fire-pot door open; to readily remove said means when the clock releases the other drafts of the furnace; to this end to obtain a long leverage upon said door-holding means; to operate said means without any additional strain on the clock works, and to obtain other advantages and results as may be brought out in the following description.

Referring to the accompanying drawings, in which like numerals of reference indicate the same parts throughout the several views,

Figure 1 is a plan of the clock controlled tripping mechanisms;

Fig. 2 is a side view of the same;

Fig. 3 is a central vertical section of the same;

Fig. 4 is a side view of a furnace showing my improved control device in connection therewith;

Fig. 5 is a front view of the furnace shown in Fig. 1 with the chain controlling the chimney draft broken away in part, and

Fig. 6 is a perspective view of the fire-pot door holding means.

In the specific embodiment of the invention illustrated in said drawings the reference numeral 1 indicates a casing adapted to inclose and support clock works 2 of

suitable construction, said casing being provided with an open front to expose the face of the clock and said front having a door 3 for closing the same to exclude dust and dirt. At the bottom and back of the casing is secured a bracket 4 which extends rearwardly and then upwardly in spaced relation to the back of the casing. Also at the bottom of the casing and depending therefrom is a post 5 upon which may be secured any suitable clamping means 6 for supporting the device in position. The particular clamping means shown provides a socketed upper end adapted to receive the post 5, said end having a transverse screw 7 therein which may be clamped against the post and secure the said clamping means at whatever position to which it is turned upon the post. Below the socketed upper end depend a plurality of ears 8 which are separated so as to take over a suitable support such as a damper bar of a furnace, and a clamping screw 9 through one of these ears is adapted to firmly secure the clamping means upon said bar. Obviously, in this manner, the clamping means may be secured at any desired position upon the damper bar and the clock casing may be turned to any position upon the clamping means desired.

The clock works 2 contained within the casing 1 includes in part a spring 10 driving through suitable mechanism a shaft 11 upon the outer or front end of which is secured the minute hand 12 of the clock. Fast upon this shaft is a relatively small gear 13 which drives a larger gear 14 fast with respect to a pinion 15, both carried by a stud 16 on the frame 17 of the clock works. In mesh with the pinion is a gear wheel 18 concentric and fast with respect to a sleeve 19 on the shaft 11 and carrying at its front end the hour hand 20. It will be understood that the relation of the various gears and mechanisms are such that the hour hand 20 will be given but one revolution to twelve revolutions of the minute hand as is usual in clocks.

Also in mesh with the pinion 15 is another gear wheel 21 corresponding in diameter to the gear wheel 18 upon the hour-hand supporting-sleeve 19, so that both said gear wheels will make exactly the same number of revolutions in a given time. This last

described gear wheel 21 is upon the front end of a shaft 22 which projects rearwardly through the frame 17 of the clock works and through a sleeve 23 which is fast with respect to and extends rearwardly from the frame of the clock works. The outer side of this sleeve provides an exterior cylindrical bearing for purposes hereinafter described, and terminates at its outer or free end in a radial flange 24. The shaft 22 projects beyond the sleeve 23, and upon this projecting end is a cam 25, which obviously will be rotated once for each revolution of the hour hand.

15 Rotatably mounted upon the exterior bearing portion of the sleeve 23 between the radial flange 24 and the frame of the clock works is a plate 26 prevented from displacement by means of the said flange. This 20 plate may be manually rotated to any position desired, and to hold it in such position a pin 27 is provided at the top of the casing adapted to be inserted in any one of the plurality of holes 28 arranged in an annular 25 series in the face of said plate. Preferably the plate is provided with at least twelve holes 28 evenly spaced and representing the twelve hours into which the clock face is usually divided. As many intermediate 30 holes to represent the half or quarter hours and so forth may be provided between each two of these twelve holes as desired, and preferably raised figures from one to twelve are integrally formed on the front of said 35 plate adjacent the twelve holes in consecutive order. When the pin 27 is inserted in any one hole it holds the plate 26 against rotating and indicates the time at which the device will operate.

40 In practice, in order to cause the mechanisms to trip at the exact time indicated by the pin in one of the holes, an adjustment is necessary between positions of the plate and the cam above mentioned. This adjustment, 45 is perhaps most readily made by shifting the position of the pin circumferentially of the clock casing. In carrying out this feature of my invention the pin is carried in a bracket 29 which is adjustable circumferentially of the casing and may be clamped in its adjusted position. This bracket comprises a foot portion 30 having a slot 31 extending circumferentially of the clock casing, and having also a pair of upwardly extending 50 lugs 32 on opposite sides of the slot suitably recessed to slidably receive the pin 27 in a direction transverse to the slot and substantially perpendicular to the setting plate. Screws 33 extending through the slot 31 into 55 the casing may be loosened to shift the bracket and tightened to retain the bracket in its shifted or adjusted position. Obviously, by this means, the bracket may be moved with the pin in one way or the other 60 as found necessary or desirable.

Upon the back of the plate 26 is a cam lever 34 which extends diametrically of the plate past its center and is hinged at one end, as by ears 35, 35, to swing in a plane perpendicular to the plate. This cam lever 70 is so formed that the cam 25 will lie beneath the same and rotate without swinging the lever except at desired intervals. In the specific arrangement shown, the cam is disk shaped providing a flat surface against 75 which the free end of the cam lever may engage. At one radial part of the disk a raised portion is provided over which the free end of the cam lever must ride as the cam is rotated, thus causing the lever to swing away 80 from the plate. Obviously, by turning the plate 26 the cam lever carried upon it will be brought into different positions, so that it will be engaged by the cam sooner or later, and by arranging the numbered holes 28 85 around the margin of the plate in proper relation, the cam lever 34 can be brought into proper position to be swung at a given hour or half hour by setting the plate 26 with the pin 27 in the hole corresponding 90 to said hour or half hour.

As positioned for illustrative purposes, the clock indicates about twelve o'clock, that is midday or midnight, and the plate 26 is set with the pin 27 in the hole marked with 95 six, indicating the mechanism will operate at six o'clock. The raised portion of the cam at this time (12 o'clock) extends straight down, and for the setting of the plate (6 o'clock) the cam lever stands 100 straight up and down with the free end up. As the clock continues to run, the cam is rotated and as the hour of six is approached the radially projecting side of the cam approaches an upward position and engages 105 the upper end of the cam lever which is swung to its maximum amplitude as the clock indicates the hour of six, after which the cam passes and allows the lever to resume its normal position. Obviously with 110 the plate set for another time than six o'clock the same operation would occur at that time instead of at six o'clock.

Of course the cam lever 34 could by its swinging movement operate any suitable 115 kind of member, but I have shown it operating a trip lever 36 standing substantially upright and preferably fulcrumed to swing in a vertical plane perpendicular to the plate 26. This lever is shown carried by the upright portion of the bracket 4 and held normally in engagement by a helical spring 37 with the cam lever 34 at a point opposite the end of the shaft 22, so as to be operated thereby regardless of what position the 120 plate 26 is turned to. The lower end of this trip lever 36 has a downwardly facing shoulder 38 adapted to take over a shoulder 39 of a releasing lever 40 pivoted horizontally to the bracket 4 opposite the lower end 125 130

of the releasing lever and adapted to hold at its other end something to be released at the given time, said trip lever thus preventing the end of the releasing lever which 5 underlies said shoulder from swinging upward until the shoulder is disengaged.

It will be noted that the bracket 4 is of channeled construction, with opposite substantially parallel side portions, and that 10 the releasing lever 40 is pivoted between said side portions so that one arm projects while the other arm lies between the side portions of the bracket and is protected or guarded thereby. Furthermore, the bracket 15 and its side portions continue upward and the trip lever 36 and its spring 37 are enclosed between said side portions. This insures that in hooking a chain over the releasing lever 40, as hereinafter described, it will 20 not be wrongly done, even in the dark. It should also be noted that the shoulder 39 has curved guide portions 64, 65 on the inner rounded end of the releasing lever extending oppositely from its opposite ends, which 25 serve to guide the trip lever into engagement with said shoulder. That is to say, when the releasing lever hangs downward it is necessary only to push its outer end upward causing the lower guide edge 64 to ride 30 over the end of the trip lever until the shoulder 39 is reached; and if the releasing lever should be thrown up too far, the trip lever will merely engage the upper guide edge 65 and be guided to the shoulder 39 as 35 the lever drops back into proper position.

One use to which my clock-operated control device is well adapted is the opening of furnace drafts at the desired hour in the morning to warm the house, and I have shown it applied to such use in Figs. 4 and 5. In said figures, the reference numeral 41 indicates a furnace having a damper bar 42 pivoted as at 43 with a weight 44 tending to normally swing the bar so that one 45 end, in this disclosure the rear end, is down and the other end up. By suitable chains or other flexible members 45, 46 connecting them to the front end of said bar, the back damper 47 may be raised or opened and the front damper 48 lowered or shut as the weighted end of the bar is raised and vice versa, as is common. I have shown my control device in Figs. 4 and 5 mounted upon the opposite end of the bar 42 from the 50 weight 44, or front end of said bar, and holding the same downward by a chain 49, extending from a lower fixed pipe or the like to the end of the releasing lever which is opposite or away from the trip lever 36. Obviously, when the cam 25 swings the cam lever 34 to disengage the trip lever 36 the releasing lever 40 lets the chain 49 slip off, and the weight 44 tips the bar 2 and operates the furnace drafts to start up the fire. 55

As a feature of the present invention I

provide a door prop 50 which, while it is desired to damper the fire off is arranged to hold the fire-pot door 51 open but which will be removed automatically as the damper bar swings to open the other drafts. 70 This door prop consists preferably of an integral piece of wire or the like bent into the desired shape as illustrated more particularly in Fig. 6. Described in detail, it comprises a shank portion 52 at one end of which is a loop 53 by means of which a chain or other flexible member 54 may connect it to the damper bar. At its other end it is bent to extend transversely of the shank portion 52 thus forming a T-head 55. 75 Spaced from the head 55 the wire is bent into a U or half loop forming a retaining portion 56 perpendicular to the shank 52 and in a plane of the shank perpendicular to the head 55. The shank 52 is preferably 80 long as compared with the distance of the loop or retaining portion 56 from the head 55. The retaining portion 56 is for engagement against the inside of the door while the T-head rests upon the top of the door 90 and abuts at one end the front of the furnace obviously preventing the door from closing. For removing the prop the looped end of the shank is drawn upwardly which causes the prop to swing on the T-head as 95 a fulcrum thus drawing the retaining portion 56 upward and removing it from behind the door which may thus close, it being observed that the long leverage obtained by the greater length of the shank permitting this to be done without the application 100 of a great deal of force.

In order that the prop may be used upon doors opening both from the right and from the left, the T-head 55 is preferably 105 made to project substantially as far one side of the shank as it does the other side, and for ease in manufacture this is obtained by bending the wire transversely to both the shank and retaining portion 56 as at 110 57 for the desired length of one side of the T-head, and then returning the wire backwardly upon itself and extending it as far on the other side of the shank. Obviously 115 on one side of the shank there will be two strands of the wire forming the T-head, and by separating these somewhat, as shown, a two point engagement will be obtained upon the top of the door when this side of the prop extends forwardly, and for obtaining a two point engagement with the door when the other end of the T-head projects forwardly, the shank may be bent laterally in a plane of the T-head as at 120 58 providing a rest separated from the T-head. Preferably this rest is adjacent the retaining portion 56 and upon the opposite side thereof from the T-head, although it might be otherwise if desired.

It will be understood, in operation, that 130

the prop is positioned horizontally at the top of the door with its retaining portion 56 holding the door open against the tendency of a spring 59 to close it. For illustrative purposes a hook 60 is shown on one end of the spring engaging the knob 61 of the door, and a chain 62 is shown at the other end of the spring secured to a fixed part of the furnace such as the pipe 63. 10 The loop 53 of the prop is connected by the chain 54 to the front end of the damper bar 42, or end which rises when the clock-operated means releases it. Thus, the upward movement of the bar 42 will swing the prop upwardly and remove the retaining portion 56 from behind the door at which time the spring 59 will draw the door closed. Preferably, the spring is attached to a fixed portion of the furnace which is above the point 15 where it is attached to the door so that the tendency will be to raise the door somewhat and will consequently cause the latch of the door to snap into its keeper.

Obviously various modifications and changes may be made in the manufacture of my improved clock-operated control device, without departing from the spirit and scope of the invention and I do not wish to be understood as limiting myself except as 20 required by the following claims when construed in the light of the prior art.

Having thus described the invention, what I claim is:

1. In a clock operated control device, the 35 combination of a rotary cam, clock means for turning said cam, a setting plate adapted to turn on substantially the same axial line as said cam, upon a stationary hub independent of the rotation of the cam, means for holding said setting plate from turning, and a cam lever on said setting plate adapted to be swung by said cam.

2. In a clock operated control device, the combination of a rotary cam, clock means 45 for turning said cam, a rotary plate concentric with said cam for setting the device to act at a given time, a cam lever on said setting plate adapted to be engaged and swung by said cam, a trip lever one end of which 50 is always in engagement with said cam lever, and means adapted to be released by said trip lever.

3. In a clock operated control device, the combination of a rotary cam, clock means 55 for turning said cam, a rotary plate concentric with said cam for setting the device to act at a given time, a cam lever on said setting plate adapted to be engaged and swung by said cam, a trip lever one end of which 60 is always in engagement with said cam lever, and a releasing lever adapted to be engaged by the trip lever and released when the cam lever is swung by the cam.

4. In a clock operated control device, the 65 combination with a casing, a rotary cam,

clock means contained within said casing for rotating said cam, a rotary plate concentric with said cam for setting the device to act at a given time, a cam lever on said plate adapted to be engaged and swung by 70 said cam, a bracket fixed to said casing and extending adjacent said cam lever, and means supported by said bracket adapted to be operated by said cam lever.

5. In a clock operated control device, the 75 combination of a rotary cam, clock means for turning said cam, a rotary plate for setting the device to act at a given time, a setting pin for holding the plate set at any desired time, a bracket for mounting said 80 pin, said bracket being adjustable in a direction transverse to the length of the pin, and means for holding the bracket in adjusted position.

6. In a clock operated control device, the 85 combination of a rotary cam, clock means for turning said cam, a rotary plate for setting the device to act at a given time, a setting pin for holding the plate set at any desired time, an adjustable bracket providing 90 bearings for said pin and having a slot transverse to the pin, and a screw in said slot for holding the bracket in adjusted position.

7. In a clock operated control device, the 95 combination of a rotary cam, clock means for turning said cam, a rotary plate for setting the device to act at a given time, a setting pin for holding the plate set at any desired time, a bracket having a slot transverse to the pin, and a pair of spaced screws in said slot for retaining said pin substantially perpendicular to the plate at all times and for clamping the bracket in adjusted 100 position.

8. In a clock operated control device, the combination with means for mounting the same, and a fixed bracket thereon with spaced side portions, of a releasing lever pivoted on said bracket with one arm projecting therefrom and the other arm between said side portions, a trip lever for holding said releasing lever, and means for tripping said trip lever at predetermined 110 times.

9. In a clock operated control device, the combination with means for mounting the same, and a fixed bracket thereon with spaced side portions, of a releasing lever pivoted on said bracket with one arm projecting therefrom and the other arm between said side portions, a spring-controlled trip lever for said releasing lever also between the side portions of the bracket, and means for tripping said trip 120 lever at predetermined times.

10. In a clock operated control device, the combination of a releasing lever having a supporting arm and an engaging shoulder with curved guide edges extending in oppo- 130

site directions from the opposite ends of said shoulder, a spring-controlled trip lever for engaging said shoulder, both said guard surfaces being adapted to guide the trip lever into engagement with said shoulder, and means for tripping said trip lever at predetermined times.

In testimony whereof I have signed this specification in the presence of two subscribing witnesses.

HENRY WILCOX.
